UNITED STATES PATENT OFFICE.

HERBERT D. WEAR AND FRANK J. MAGINNIS, OF LAKE CITY, MINNESOTA, ASSIGNEES
OF ONE-THIRD TO FRED J. LUTH, OF LAKE CITY, MINNESOTA.

AUTOMATIC DOOR-RELEASER.

1,195,882.

Specification of Letters Patent. Patented Aug. 22, 1916.

Application filed April 18, 1916. Serial No. 91,945.

To all whom it may concern:

Be it known that we, HERBERT D. WEAR and FRANK J. MAGINNIS, citizens of the United States, residing at Lake City, in the 5 county of Wabasha and State of Minnesota, have invented new and useful Improvements in Automatic Door-Releaseers, of which the following is a specification.

The invention relates to door operating 10 mechanism and more particularly to mechanism designed for opening and closing the tonneau doors of an automobile, with the controlling means arranged so that it may be actuated by the driver without the necessity of leaving his position at the wheel.

The invention is particularly directed to a mechanism, duplicated for each rear door, and including a means for unlatching the door and subsequently swinging the door to 20 an open position, the mechanism being adapted for reverse movement to swing the door to a closed position where it is automatically latched, the invention including the provision of means whereby the driver 25 may selectively operate the mechanism for either door, or simultaneously operate both doors at will.

The invention in the preferred form of 30 details will be described in the following specification, reference being had particularly to the accompanying drawings, in which:

Figure 1 is a view in elevation of the improved mechanism, a sufficient portion of 35 the automobile being illustrated diagrammatically to show the position of the parts. Fig. 2 is a plan view of the same. Fig. 3 is a section on line 3—3 of Fig. 1. Fig. 4 is a plan of the driver's control mechanism. 40 Fig. 5 is a perspective view showing the connection with the hinge of the door.

In the preferred embodiment of the present invention illustrated in Figs. 1 to 5, inclusive, there is mounted in the forward 45 portion of the vehicle, preferably convenient to the driver, a transverse shaft 1, on which is supported the operating parts for the respective doors. As these parts are in duplicate, a detail description of one will 50 suffice for both, it being understood that the respective duplicate parts are located in spaced relation on and in effect at opposite ends of the shaft 1. The operating mechanism includes a sleeve member 2, freely rotatable on the shaft 1, from which extends a

rigid upright arm 3, and from which depends a rigid operating member 4, the detailed description of which will later appear. To the upper end of the arm 3 is secured a rod 5 which extends rearwardly to 60 a position slightly in advance of the door to be operated, and is connected to an upright rod 6 pivotally connected at 7 in a bracket 8 secured to a fixed part of the machine. The upper end of the rod 6 is in turn connected to a rod 9, which is at its rear end in engagement with a plunger 10 mounted for operating movement and guided in a bracket 11. The bracket 11 is arranged in such position with relation to the latch 12, 70 usually employed for holding the door 13 in closed position, that in the relatively rearward movement of the plunger the latch will be forced to a position beyond the keeper, to thus free it for opening movement. To the lower end of the operating member 4 is connected a rod 14 which extends to a position in rear of the door to be opened and is there connected to an upright rod 15 pivotally secured at 16, in a bracket 80 17, fixed to the automobile structure. The upper end of the rod 15 is slidably mounted upon a rod 18, which latter is slidably mounted in brackets 19 secured to the automobile structure. Collars 20 are fixed upon the rod 18 on opposite sides of the rod 15, and intermediate the collars and said rod 15 are arranged coiled springs 21, these springs being of appropriate tension for the work to be performed. The rod 18 normally terminating somewhat in rear of the door 13 and preferably in alinement with one of the hinges thereof. That end of the rod 18 next the door is pivotally connected to a link 22, which extends through the immediately adjacent hinge leaf 23, and is pivotally connected at 24 to the remaining hinge leaf 25. The hinge leaf 25, which is the leaf connected to the door, is therefore fixed against other than a pivotal movement with respect to the link, while the latter moves freely through the hinge leaf 23, which is the leaf fixed to the automobile structure, said leaf 23 being of course slotted to permit a lateral movement of the link. The pivoted rods 6 and 15 are reversely mounted with respect to their play as levers, that is to say, the rod 6 is pivotally mounted to favor the operating end thereof, whereby 105 to give necessary strength to display the 110

leaf, while the rod 15 is mounted to favor the upper portion thereof whereby to increase the movement of said end with respect to the opposite end.

5 As previously noted the mechanisms so far described are duplicated, one for each door, and the operating members 4 are thus arranged side by side on the shaft 1, as will be plain from Fig. 2. A pedal 26 is mounted 10 for lateral swinging movement at 27 upon a bracket 28, which in turn is rotatably supported upon the shaft 1, between the operating members 4. The pedal is provided on each side with lugs 29, and the operating 15 members provided with extensions 30 formed to be engaged by the lugs in the depression of the pedal. The rod 14 is provided in advance of its connection with the operating member 4 with a rod extension 31 20 which is provided with a terminal disk 32, between which and a bracket 33, fixed on the automobile structure, is arranged a coiled spring 44. The pedal 26 is provided with a foot piece 35 and preferably with a depending notched bar 36 to engage a dog 37, fixed on the automobile structure whereby the pedal may be locked in any desired position at the will of the user. In this form 25 of the device it will be understood that the driver on depressing the pedal locks the operating member to independently move forwardly the shaft 5 and rearwardly the shaft 14. The forward movement of the shaft 5, will, from the obvious movement of the parts connected therewith cause an opening 30 movement of the latch, thus unlocking the door. During this operation, the rearward movement of the rod 14 has moved the upper end of the rod 15 forward or toward 35 the door. This compresses the spring 21 in advance of said rod 15. Immediately therefore the latch is released, the spring operates to move the rod 18 toward the door with the effect to spread the hinge leaves, thus opening 40 the door. Upon the release of the pedal, the parts return to normal position, the spring 34 operating to draw upon the rod 14 45

for the effect to cause the reverse movement of the hinge plates and independently close the door, the latching operation of the door 50 being automatic as the plunger 10 has been withdrawn.

From Fig. 2 it will be apparent that by the pivotal support of the pedal the latter may be swung laterally to engage either 55 operating member at will, and hence operate either door at will, or if maintained in a central position, may, through a single depression, operate both doors simultaneously.

It is of course to be understood that all 60 operating parts, except those in which accessibility is required for operation, such as the pedal, will be concealed between the walls of the automobile, and under the body, so that practically no part of the device is 65 visible to the occupant of the tonneau.

What is claimed is:

1. A door operating mechanism including a shaft, an operating member mounted thereon, rods connected to the operating member 70 on the respective sides of the shaft, an unlatching mechanism connected to one rod, and a spring tensioning member connected to the other rod, a door swinging mechanism connected to the spring tensioning mechanism and operable solely thereby, and a pedal to engage and actuate the operating member.

2. A door operating mechanism including a shaft, an operating member mounted thereon, rods connected to the operating member on the respective sides of the shaft, an unlatching mechanism connected to one rod, and a spring tensioning member connected to the other rod, a door swinging mechanism 85 connected to the spring tensioning mechanism and operable solely thereby, and a pedal to engage and actuate the operating member, means for returning the operating member to normal position. 90

In testimony whereof we affix our signatures.

HERBERT D. WEAR.
FRANK J. MAGINNIS.
